UNITED STATES PATENT OFFICE.

LYMAN BANKS, OF MUSCATINE, IOWA.

CONVERTIBLE COT AND SEAT.

SPECIFICATION forming part of Letters Patent No. 339,131, dated April 6, 1886.

Application filed January 28, 1886. Serial No. 190,069. (No model.)

To all whom it may concern:

Be it known that I, LYMAN BANKS, a citizen of the United States of America, residing at Muscatine, in the county of Muscatine and State of Iowa, have invented certain new and useful Improvements in Convertible Cots and Seats, of which the following is a specification, reference being had therein to the accompanying drawings.

10 My invention relates to convertible cots and seats; and it consists of an ordinary cross-legged cot constructed to be readily converted from a cot into a seat, and vice versa, as hereinafter set forth.

15 In the accompanying drawings, Figure 1 is a perspective view of the device adjusted in position for use as a cot. Fig. 2 is a perspective view of the cot converted into a seat. Fig. 3 is an end elevation of the cot. Fig. 4 20 is an end view of the cot converted into a seat. Fig. 5 is a detached view of the coupling-bolt.

A A' designate the rails of the cot, and B B' the cross-legs, which are securely attached 25 to the rails in any suitable manner.

C designates the ordinary covering of the cot, made of canvas or any suitable fabric, attached to the rails in the usual manner.

D designates the seat-supports, made of 30 wood or any other suitable material, having one end pivoted by bolts or screws to the legs B', near the rail A', the other ends of the supports being free and adapted to catch as pawls in the notches in the legs.

35 The cross-legs B B' are each provided with two round holes, c d, and slots of less diameter than the holes and communicating with them, forming key-hole-shaped openings, to receive the bolts f, provided on their ends with 40 the locking-bits or angular projections h, the bolts being made long enough to extend through both legs, so that the hooks will catch and hold against the inner surface of the cross-legs.

45 The legs B are provided with notches a, in which the free ends of the supports D rest when the device is used for a seat. The cot bolt-holes c are located, as usual, about the central portion of the legs, and the seat bolt-holes d are located in relation to the cot bolt-holes so that when the device is converted 50 into a seat the front rail, A', will be the prop-

er height for a seat, and the back rail, A, will be in proper position to form a seat-back, as shown. Ordinarily, for this purpose, the 55 seat bolt-holes d are located in the leg B, supporting the back rail, A, about one-tenth of the length of the leg below the cot bolt-holes c, and in the leg B', supporting the front or seat rail, A', the seat bolt-holes are 60 about one-fifth the length of the leg above the cot bolt-holes c. It is evident that the relative positions of these bolt-holes may be varied to obtain any required height of the seat-rail and inclination of the back of the 65 seat.

The seat-supports D are made the required length, so that when used for a seat the free ends rest in the notches a in the legs B, for the purpose of holding the rail A' in position to 70 allow the cover C to sag sufficiently to form a comfortable seat, as shown in Figs. 2 and 4; also to give firmness and strength to rail A'. When the device is used as a cot, the supports D are pendent.

To convert the cot into a seat, the bolts f are placed in the holes d, the free ends of the supports D being adjusted in the notches a, and the frame and covering take the position shown in Figs. 2 and 4.

The cross-legs are securely coupled together by means of the bolts f, having the angular bits or hooks h, which, by turning the bolts partly around, after being inserted through both legs, catch and hold against the inner 85 surfaces of the inner legs.

It is evident that in coupling the cross-legs the coupling-bolts to be inserted or removed must be placed in position for the locking bits or hooks h to be in range with the slots. 90 Thus it is shown that by very simple and inexpensive devices an ordinary cross-legged cot is readily convertible into a convenient and comfortable seat, which is readily convertible back again into a cot.

What I claim as new, and desire to secure by Letters Patent, is—

1. In a convertible frame, the combination of the supporting-legs B B', each provided with bolt-holes c d, located in positions relative to each other, as set forth, and the coupling-bolts f, adapted to couple the legs together, to form a cot or a seat frame, substantially as and for the purposes described.

2. The combination of the rails A A', the legs B B', provided with the key-hole openings c d, located in relative positions to each other, as set forth, to enable the legs to be
5 coupled together to form a cot or a seat frame by changing the crossing-places of the legs, the coupling-bolts f, having the locking-hooks h, the notches a a in legs B, and the pivoted

supports D, substantially as and for the purposes described.

In testimony whereof I affix my signature in presence of two witnesses.

LYMAN BANKS.
